UNITED STATES PATENT OFFICE.

MATTHEW P. BENSON, OF TROY, AND MILTON M. WIENER, OF NEW YORK, N. Y.

METAL-FACE-PLATE BRUSH.

Application filed February 1, 1922. Serial No. 533,324.

To all whom it may concern:

Be it known that we, MATTHEW P. BENSON and MILTON M. WIENER, both citizens of the United States, residing, respectively, 5 at Troy, in the county of Rensselaer, and New York, in the county of New York, both in the State of New York, have invented certain new and useful Improvements in Metal-Face-Plate Brushes, of which the following is a specification.

This invention relates to the manufacture of toilet brushes or the like and has particular reference to the manner of construction and attachment of a face plate of metal or 15 other analogous material.

Among the objects of the invention is to provide a brush the back of which is of the most sanitary construction and one which possesses the neatest possible appearance as 20 well as being as nearly water proof as any composite article may be.

More specifically stated the invention comprises a novel form and construction of face plate, the same having features bearing both 25 upon the appearance of the finished brush and improved locking means for securing the same in place in connection with the back.

With the foregoing and other objects in 30 view the invention consists in the arrangement and combination of parts hereinafter described and claimed, and while the invention is not restricted to the exact details of construction disclosed or suggested herein, 35 still for the purpose of illustrating a practical embodiment thereof reference is had to the accompanying drawings, in which like reference characters designate the same parts in the several views, and in which—

40 Figure 1 is a plan view of the face portion of a brush, parts being broken away.

Fig. 2 is an enlarged cross sectional detail on the line 2—2 of Fig. 1.

Fig. 3 is a fragment of the face plate 45 projected from Fig. 2.

Referring now more specifically to the drawings, 10 indicates a brush made ordinarily of wood or the like and so shaped as by routing on the face thereof to provide 50 a cavity 11, the periphery of the cavity being under-cut as shown at 12.

The face plate above referred to is shown at 13 and may be understood as being formed from a single piece of sheet metal

in the convex portion of which are formed 55 a multiplicity of holes 14 in which a corresponding number of groups or bundles of bristles 15 are fixed in any suitable manner, the head ends of the bristles projecting from the face plate into about the mid portion of the cavity. The formation of the face plate includes a flange 16 projecting into the peripheral portion of the cavity 11 to about the bottom thereof and perpendicular to said bottom or the general plane of 60 the face plate, irrespective of the form the bottom of the cavity may be made to assume. In other words, the flange 16 extending around the face plate forms with the undercut 12 an annular space 17 of substantially 65 triangular form in cross section.

As metal face plates have been made heretofore the part corresponding to the flange 16 is bent directly inward from the extreme outer edge of the exposed portion of 75 the face plate. Because of various working conditions such as variations in size or quality of the stock, the carefulness of the workmen, the precision of the routing tools, or the like, it is impossible for all of the 80 cavities to be formed or routed with such precision as will preclude the loss or scrapping of at least a considerable number of brush backs. In other words, as heretofore practised the periphery of the cavity will 85 oftentimes show a roughness or unevenness along the extreme edge of the face plate, which condition renders the brush, so made up, at best a second and one which lacks neatness of appearance as well as being 90 likely to accumulate dust or dirt and so become unsanitary and most unsightly. In this improvement, the exposed surface portion of the plate 13 overlaps the adjacent edge of the undercut back as indicated at 18, 95 for the formation of which the metal or stock from which the plate is formed is bent or crimped sharply upon itself, and then finally the flange is projected inward from the doubled overlapping portion and so 100 is fitted into the cavity directly past said adjacent edge of the under-cut portion. The overlapping double portion of the face plate thus serves to obscure any possible roughness or unevenness incident to the formation or 105 routing of the cavity in the back 10. Moreover, this exposed edge of the face plate, being rounded due to the folding upon itself,

produces an unusually pleasing finish for this part of the completed brush. It follows therefore that no water or other extraneous matter can possibly get into the joint between the edges of the plate and the back.

Any suitable means may be provided to secure the face plate in the position indicated in the cavity. To this end it is best to introduce forcibly into the cavity 10 a plastic substance 19 which on becoming hard serves to lock the parts together making a substantially solid brush body. The idea of introducing this plastic material being well known need not be further described here.

The flange 16 is shown provided with a row of holes 20 of any suitable form or size which if remote from the extreme edge of the flange will not materially weaken the 20 same. The plastic material when forced into the cavity will likewise be projected outward into and through the holes 20, giving added holding power to the plastic material when it becomes hard. Each portion 25 of material projecting into one of the holes serves as a holding spur to prevent the loosening of the face plate. This function is augmented by the formation of the under-cut space 17 into which a portion of the material passing through the holes 20 may be forced. Obviously any plastic material 30 which occupies the under-cut space upon becoming hard will act as a wedge and so additionally lock the flange 16 in place.

35 We claim:

1. In combination, a wooden brush back having a routed cavity bounded by a rim, a face plate of sheet material having a straight flange projected into the peripheral 40 portion of the cavity and having a ribbed portion projecting outward and overlapping the joint between said flange and, the rim

portion aforesaid of the back and means to lock the face plate in place, substantially as set forth.

2. A device as set forth in claim 1 in which the overlapping portion of the face plate is formed by crimping the material of the plate sharply upon itself forming a smooth rounded finishing portion for the 50 exposed edge thereof in the finished brush.

3. The combination with a brush back having an under-cut rim portion forming a cavity, of a metal face plate having a flange projecting into the periphery of the cavity 55 perpendicular to the general plane of the face plate and leaving an annular space incident to said under-cut while the outer surface of the flange substantially meets the adjacent edge portion of the back rim, 60 bristles projecting through said plate, the plate flange being perforated, and means projected through the face plate flange perforations to lock the same in place.

4. The combination with a brush back 65 having a cavity, of a metal face plate having a flange projecting into the periphery of the cavity, said face plate being perforated, bristles extending from the cavity aforesaid through said perforations, and a 70 body of plastic material serving to lock the bristle ends within the cavity and the face plate flange in the periphery of the cavity, a portion of the plastic material acting between the outer surface of the flange and 75 the adjacent wall of the cavity.

5. A brush as set forth in claim 4 in which the face plate flange is perforated and portions of the plastic material project radially through said perforations.

In testimony whereof we affix our signatures.

MATTHEW P. BENSON.
MILTON M. WIENER.
